UNITED STATES PATENT OFFICE.

AARON MENDELSOHN, OF SAN FRANCISCO, CALIFORNIA.

CIGAR FOR ASTHMA.

No. 811,942.

Specification of Letters Patent.

Patented Feb. 6, 1906.

Application filed August 21, 1905. Serial No. 275,148.

To all whom it may concern:

Be it known that I, AARON MENDELSOHN, a citizen of the United States, residing in the city and county of San Francisco and State 5 of California, have invented new and useful Improvements in Cigars for the Relief of Asthma, of which the following is a specification.

My invention relates to a device for the relief of asthma and similar troubles.

It consists of a cigar manufactured with a filling of cherry-leaves and stramonium having an exterior wrapper of tobacco-leaves.

The stramonium when dried is in the form 15 of an elongated stem having a bulbous end, and these stems are cut of such length as to form the desired length of the cigar. These stems form a center support for the remainder of the cigar, as shown at A. As many of 20 these stems may be bunched together as are required to form a suitable diameter, and around this central mass are arranged cherry-leaves, as shown at 2. These leaves form an exterior coating for the central stems, and 25 they may also, if desired, be inserted between and compressed with the stems if more than one of such stems is employed. The whole is then inclosed in a tobacco-leaf wrapper 3, which is coiled around the outside, forming a 30 complete cigar.

In the drawings, Figure 1 is a longitudinal view of a cigar, partially in section. Fig. 2 is a transverse section.

I prefer to make these cigars somewhat 35 slender and of considerable length. The upper end of the cigar is completed by twisting it, so as to retain the wrapper in place. The lower end may be cut square or in any suitable manner. Any suitable material may be 40 used for a wrapper; but I have found tobacco-

leaves to be the most satisfactory on account of the character of the leaf and its peculiar adaptability for making such wrappers.

In using these cigars or cigarettes the patient lights the cigar and takes a small number of whiffs of the smoke. As many as five or a few more may be taken, and the smoke should be swallowed or drawn inwardly and then blown out through the nostrils. After 45 a short rest a few more whiffs may be taken, and the coughing will be checked. The cigar or cigarette may then be extinguished and again used whenever a coughing fit takes place or when a patient lies down for rest at night.

Having thus described my invention, what I claim, and desire to secure by Letters Patent, is—

1. A cigar or cigarette having the center formed of the stems and heads of stramonium and cherry-leaves inclosing or intertwining therewith to form a binder throughout the length of the stramonium filling serving as a binder therefor, and an exterior wrapper of tobacco-leaves.

2. An article of manufacture consisting of stramonium-stems clustered and disposed longitudinally to form a central filling, cherry-leaves inclosing or intertwined therewith a binder throughout the length of the stramonium filling serving as a binder therefor and an exterior wrapper of tobacco-leaves.

In testimony whereof I have hereunto set my hand in presence of two subscribing witnesses.

AARON MENDELSOHN.
